United States Patent

Des. 240,186
Patented June 8, 1976

240,186

TABLE

Leon Rosen, Scarsdale, N.Y., assignor to The Pace Collection Inc., New York, N.Y.

Filed Jan. 17, 1975, Ser. No. 541,891

Term of patent 14 years

Int. Cl. D6—03

U.S. Cl. D6—177

FIG. 1

FIG. 2

FIG. 3

FIG. 4

FIG. 1 is a perspective view of a table showing my design;

FIG. 2 is a plan view;

FIG. 3 is a side view, the oposite side view being the same; and

FIG. 4 is an end view, the opposite end view being the same.

I claim:

The ornamental design for a table, as shown and described.
